BOTTLE CARRIER

Charles F. Koerber, Clay Township,
St. Joseph County, Ind.

Application April 11, 1949, Serial No. 86,713

12 Claims.

(Cl. 224—45)

1

This invention relates to improvements in bottle carriers, and particularly to a carrier for beverage bottles, which will enable a purchaser who buys a number of bottles to carry them easily and conveniently.

The primary object of the invention is to provide a bottle carrier of this character which can be formed from a single rectangular blank of cardboard or other suitable material, without waste, and which does not require the use of stiches, staples, glue or other means to set up or erect the carrier.

A further object is to provide a carrier of this character which can be shipped and stored in flat form and which can be erected and loaded quickly and easily.

A further object is to provide a bottle carrier of this character which is easy to manufacture, inexpensive, which will not interfere with the stacking of bottles, and which is provided with a novel reinforced hand grip.

A further object is to provide a bottle carrier formed from a blank having one end portion folded to rectangular form with bottle receiving apertures at the top of the rectangular portion, and wherein the other end of the blank is apertured in spaced relation to its end for register with the first apertures when substantially parallel thereto and adapted, when bearing the weight of bottles, to be positioned at an inclination binding at the upper end of the bottles to provide a top fulcrum point located at the reduced upper neck portion of the bottles.

A further object is to provide a bottle carrier of this character comprising a scored blank having a plurality of bottle-receiving openings arranged in two longitudinally spaced groups, with the openings of each group transversely aligned and spaced from the end of the blank adjacent thereto, and also having means for interlocking one end portion of the blank with the portion of the blank between said groups of openings, whereby, when said blank is bent along its score and its end portion is interlocked by said means, a plurality of bottles can be inserted through pairs of aligned openings to rest upon a transverse portion of the blank anchored by said interlocking means, and whereby said carrier can be suspended from its opposite end portion.

A further object is to provide a bottle carrier formed from a scored and folded blank having a tab at an intermediate portion thereof adapted to interlock with an end portion of the blank to define a bottle-receiving socket portion, wherein said interlocking parts are located to be engaged by a bottle and retained thereby against release.

Other objects will be apparent from the following specification.

In the drawing:

Fig. 1 is a vertical transverse sectional view taken on line 1—1 of Fig. 3.

2

Fig. 2 is a vertical sectional view similar to Fig. 1 and illustrating the carrier constructed to carry bottles of a smaller size than those shown in Fig. 1.

Fig. 3 is a vertical longitudinal sectional view taken on line 3—3 of Fig. 2.

Fig. 4 is a plan view of the blank from which the bottle carrier shown in Fig. 1 is constructed.

Fig. 5 is a plan view of the blank from which the bottle carrier illustrated in Fig. 2 is constructed.

Referring to the drawings which illustrate the preferred embodiment of the invention, and particularly to Figs. 1 and 4, the numeral 10 designates a blank of cardboard, paperboard, fiberboard or any other sheet material found suitable, and preferably characterized by rigidity and strength sufficient to support the weight of a number of beverage bottles and adapted to be folded and to pivot along fold lines. The blank is of substantially rectangular form, as best seen in Fig. 4, and is provided with a plurality of transverse score lines 11, 12, 13, 14, 15, 16, 17, 18 and 19, which are substantially parallel to each other and along which the blank is adapted to be folded. V-shaped cuts 20 are formed at the opposite sides of the blank with their apices located adjacent the score line 17 and the edges extending in equiangular relation therefrom to terminate adjacent to the score lines 16 and 18.

The portion of the blank between the score line 11 and the end of the blank defines a locking panel 21 of relatively narrow width. The portion of the blank between the score lines 11 and 12 defines a socket panel 22 which is of a width substantially equal to or slightly greater than the diameter of the cylindrical body portion 23 of a beverage bottle of the conventional character having a reduced diameter upper neck portion 24. The socket panel 22 is provided with a plurality of openings 25 formed therein, each of a width or size sufficient to snugly receive the body portion 23 of a bottle. As here illustrated, the openings 25 are arranged in transverse alignment with the outermost opening spaced from the side edges of the blank and the openings being spaced apart by web portions. Where three openings are formed in the blank, as illustrated in Fig. 4, two of the openings will be of circular character and the other opening will be defined by straight side edges 26 coinciding with the score lines 11 and 12 and each of a length equal to the diameter of the circular openings. The other two edges of this opening will be characterized by angularly extending portions defining tabs 27, as seen in Fig. 4. A longitudinal score line 28 will extend along the base of each of the tabs 27 and, as here shown, will extend substantially tangent to the adjacent circular bottle-receiving opening 25.

The portion of the blank between the score lines 12 and 13 defines a riser panel 29, and the

portion of the blank between the score lines 13 and 14 defines a socket bottom panel 30. The portion of the blank between the score lines 14 and 15 defines a second riser panel 31 which is of substantially greater height than the riser panel 29. The riser panel 31 is slotted substantially at its center by a U-shaped cut or slit 32 which defines an elongated tongue 33 whose free edge is located adjacent to the score line 14. This tongue 33 has a U-shaped slit 34 formed therein to define a tab 35 whose free edge is spaced from the ends of the parallel slit 32 which define the tongue 33 a distance slightly greater than the height of the locking panel 21.

A portion of the blank between the score lines 15 and 16 defines a transverse panel 36. This panel is preferably of substantially the same dimension or size as the panel 22 and has formed therein the openings 25, 26 separated by the tabs 27 of substantially similar arrangement and construction to the openings formed in the panel 22.

The portions of the panel between the score lines 16 and 17, and 17 and 18, define handle portions 37 and are preferably similar in construction. These two panels are provided with slits 38 of substantially the same size and preferably of C-shape, which cooperate with score lines 39 connecting the ends of said slits to define tab portions 40.

The portion 41 of the blank between the score lines 18 and 19 is preferably of the same size and shape as the panels 22 and 36 and has openings 25, 26 and tabs 27 formed therein similar to those in the panel 22. A short panel portion 42 extends between the score line 19 and the adjacent end of the blank, said panel preferably being of a dimension longitudinally of the blank slightly less than the spacing between the score line 15 and the adjacent ends of the slits 32 which form the tongue 33 in the panel portion 31.

When it is desired to set up or erect a bottle carrier from the blank shown in Fig. 4, the blank is first folded along the score lines 11, 12, 13 and 14 so that a tube is formed of substantially rectangular cross-section with the panel 22 forming the top of the tube, the panel 30 forming the bottom of the tube, and the panels 29 and 31 forming the side walls of the tube. The panel 21 is bent upwardly out of the contour of the tube to bear flat against the panel 31 and is tucked behind the tongue 33, being passed to the upper end of the tongue and clear of the tab 35 which is then bent laterally so that the panel 31 may be moved downwardly to be interlocked between the tab 35 and the body of the tongue 33, as best shown in Fig. 1. The tab 35 engages the panel 21 at the inner edge of said panel defined by the left-hand cut edge 26, as seen in Fig. 1. It will also be observed in Fig. 1 that the device does not necessarily form a true rectangular tube inasmuch as the panel portion 22 may be somewhat inclined.

The upper or opposite portion of the blank is then folded at score line 17 to bring the panels 37 into face engagement with one another, which also entails bringing the panel 41 into face engagement with the panel 36, and the panel 42 into face engagement with the panel 31. Thereupon the blank is folded along the score lines 15 and 19 to position the superimposed blank 36, 41 in substantially horizontal position as illustrated in dotted lines in Fig. 1, and the blank is also folded along the score lines 16 and 18

5 to position the engaged handle portions 37 substantially vertical, as also seen in Fig. 1 in dotted lines. The tabs 40 outlined by the slits 38 are then folded or return bent, as best seen in Fig. 1, so as to form openings 43 which constitute finger openings.

10 The device is now ready to be loaded, and, for this purpose, the upper end portion of the carrier is held in position illustrated in dotted lines in Fig. 1. This serves to position the openings in the panels 36 and 41 in substantial register with the openings in the panel 22 so that the bottles may be inserted through the registering openings in the panels 36, 41 and 22 with their bottoms resting upon the bottom panel 30. It will be understood that the tabs 27 positioned between the bottle-receiving openings in each of the panels 25, 36 and 41 will have been folded along their 15 score lines 28 to assume a substantially vertical position to form separators between the bottles. Inasmuch as the score lines 28 occur and extend substantially tangent to the circular openings 25, the thickness of the tabs 27 determines the spacing between the bottles. It will be observed in Fig. 1 that the score lines 15 and 19 are located at a level upon the bottle 23 substantially coinciding with the level at which the part-spherical shoulder 44 merges with the cylindrical body portion 23 of the bottle. Consequently, 20 after the carrier has been loaded and the upwardly projecting panels 37 are gripped, as by passing the fingers through the finger holes 43, the upper portion of the carrier is swung to the full line position illustrated in Fig. 1 with the panels 36 and 41 assuming an inclined position and the portions of the bottle-receiving openings adjacent to the upright panels 37 engaging the neck portions 24 of the bottles.

25 In the form of the device shown in Fig. 4, three openings are formed in each of the panels 22, 36 and 41. This number is particularly well suited for carriers of a size to carry quart bottles. It will be understood, however, that a greater or 30 smaller number of openings may be formed. 35 Thus openings may be provided to receive two bottles or to receive four or more bottles.

The weight of the bottles is sustained by the bottom panel 30 and the opening in the panels 22, 36 and 41 serve to so position the bottles as 30 to apply that force and weight of the bottle in a substantially vertical downward direction as opposed to a downwardly and laterally directed manner which would tend to tilt the bottles. The 35 bottle-receiving openings, and particularly the openings in the panels 36 and 41, thus act to prevent distortion of the folded tubular lower socket portion for the bottle which would tend normally to pull the panel 21 away from the panel 31 and to release the interlock provided by the tongue 33 and the tab 35. Attention is also directed to the fact that the tongue 33 and tab 35 are so located or positioned that they are engaged by the cylindrical portion of the bottle 23 and held thereby against lateral displacement. 40 In other words, as best seen in Fig. 1, the cylindrical portion of the bottle holds the tongue 33 substantially in the plane of the panel 31 and prevents it from being pulled to the left in Fig. 1 in the manner which it would tend to be pulled by virtue of the application of the weight of the bottle to the bottom panel 30.

45 Another characteristic of the device is that when its end portion 37 is gripped and the carrier is lifted, the panel portions 37 lie alongside the bottle neck 24 and press laterally thereagainst

to forcibly urge the bottles into engagement with the panel 31. This entails the carrying of the bottles in a position tilted a few degrees from vertical position but not sufficiently to be noticeable or objectionable, and in effect fulcrums the device and the bottles in such a manner as to preserve the interlock of the parts and prevents the disassembly of the device or the release of the bottles. At the same time removal of the bottles from the device can be accomplished very easily by simply lowering the panels 36, 41 to the horizontal position illustrated in dotted lines in Fig. 1, whereupon the bottles can be lifted out of the carrier without difficulty.

It will be observed that no staples, stitches, glue or other securing means is required in the device for its proper functioning or for strength. However, it will be apparent that a partial setup of the device may be secured without loss of the flat knocked-down condition thereof by supplying the blank folded along score line 17 and stapled at the handle panels 37. This is strictly an alternative construction which increases somewhat the strength of the unit but is not required for operative functioning of the device. Also, if desired, panel 21 may be stapled or glued to panel 31.

The device illustrated in Figs. 2, 3 and 5 is designed to receive four bottles of smaller size than the bottles received in the Fig. 1 device. For example, assuming the bottles illustrated in Fig. 1 are of one quart size, the bottles illustrated in Fig. 2 may be of the common 12 ounce size or any other size desired. The smaller size of the bottles and the reduced weight thereof, compared to the quart size bottle, permits a greater number of bottles to be carried in a device formed of a material of a given quality and strength, and the smaller diameter of the bottles enables a larger number to be carried without substantially increasing the width of the carrier.

The blank from which the carrier illustrated in Figs. 2 and 3 is formed is illustrated in Fig. 5 and is substantially of rectangular form and is provided with the score lines 11, 12, 13, 14, 15 and 16 which correspond to score lines of the blank shown in Fig. 1 which show the same numbers. These score lines cooperate to define the panels 21, 22, 29, 30, 31, 36 and 37 which are similar to the panels of the blank shown in Fig. 1 which bear the same numerals. It will be understood, however, that differences will occur in various blanks as required by the difference in the size of the bottle to be received thereby. Thus, in the blank shown in Fig. 5, panels 22 and 36 will have four or any other selected number of bottle-receiving openings formed therein, including the circular or part-circular end openings 25 and the intermediate openings defined by straight edges 26 coinciding with the score lines 11 and 12. The tabs 27 are formed between each pair of adjacent openings, and these tabs are adapted to be bent along the score lines 28 in the same manner described above.

It will also be observed in Fig. 5 that two interlocking tongues 33 are formed in the panel 31 instead of the single tongue in the blank shown in Fig. 4. Each of these tongues has the tab 35 formed therein spaced from the ends of the slits 32 defining the tongue 33 a distance equal to or slightly greater than the dimension of the panel 31 lengthwise of the blank. The tongues 33 are so located and arranged, preferably equally spaced from the longitudinal edges of the blank,

that they are adapted to engage the panel 21 at the straight edges 26.

The right-hand end of the blank is preferably tapered at 46, and a score line 47 extends parallel to the scores 11-16 of the blank and adjacent to the right-hand end of the blank. The portion 48 of the blank forms a tongue adapted to be return bent into face engagement with the handle portion 37. The handle portion 37 has the C-shaped slots 38 formed therein to outline tabs 40 which are adapted to be bent along the score lines 39. The tongue 48 has tabs 49 outlined in part by the outer edge of said tongue, and in part by curved slits 50, said tabs 49 being adapted to be folded along score lines 51 parallel to the score line 47 and spaced therefrom the same distance that the score lines 39 are spaced from the score line 47. Consequently, the tabs 40 and 49 register when the tongue is folded along the score line 47, and the tabs 49 may be pushed through the openings outlined by the tabs 40 and return bent as illustrated in Fig. 2 to provide a convenient hand grip.

It will be apparent that the construction of the carrier shown in Fig. 2 from the blank shown in Fig. 5 possesses all of the advantages of the construction previously described herein, and is erected and filled in the same manner as the Fig. 1 device, with the exception that the carrier is of single thickness throughout and not of double thickness at its upper portion as in the Fig. 1 device. Specifically, it will be apparent that the relation of the bottles to the carrier with two lateral contact points at one side of the bottles, that is, contact points at handle 37 and panel 29, with a third lateral contact point at its opposite side, namely at the panel 31 positioned in part at a level between the first mentioned contact points, is provided in this form in the same manner as in the Fig. 1 form. Observe also that the bottles in this form serve to hold the interlock which forms the tubular bottom socket in position is provided in this device in the same manner that it is provided in the Fig. 1 device.

While the preferred embodiment of the invention has been illustrated and described herein, it will be understood that changes in the construction may be made within the scope of the appended claims without departing from the spirit of the invention.

I claim:

1. A bottle carrier comprising a blank having a plurality of substantially parallel scores, said blank being folded along said scores to define a tube at one end, said blank being slitted to define a tongue interlocking with the end of the tube-forming portion of said blank, the opposite folded end portion of said blank including a transverse panel and a terminal handle-forming panel, said transverse panel and the upper portion of said tube each having a bottle-receiving aperture therein.

2. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein.

3. A bottle carrier comprising a transverse tubular portion including top, bottom and side walls, one of said side walls being taller than the other, a transverse panel carried by the upper

end of said tall side wall, and an upwardly extending handle panel carried by the free end of said transverse panel, said top wall and transverse panel having registering bottle-receiving apertures therein, said tubular portion, transverse panel and handle panel being formed from a single blank, said tall side wall having a tab struck therefrom and interlocking with the end of said blank to hold said tubular portion in operative position.

4. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said tubular portion, transverse panel and handle panel being formed from a single blank, said tall side wall having a tab struck therefrom and interlocking with the end of said blank to hold said tubular portion in operative position, said tab being located adjacent one of said apertures for engagement by a bottle received in said aperture.

5. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said tubular portion, transverse panel and handle panel being formed from a single blank, a tab struck from said tall side wall, said blank including an end panel in face engagement with said tall side wall and interlocking with said tab to hold said tubular portion in operative position.

6. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said tubular portion, transverse panel and handle panel being formed from a single blank including an end panel projecting from said tubular portion in face engagement with said tall side wall, a tongue struck from said tall side wall in longitudinal alignment with one of said bottle openings and joined to said wall at its upper end, and a tab struck from said tongue with its free end adjacent the base of said tongue and spaced therefrom a distance at least equal to the height of said end panel whereby said end panel fits between said wall and tongue and is retained at selected elevation by said tab.

7. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said handle panel including a return bent panel in face engagement therewith, said handle panel and return bent panel having

registering tabs struck therefrom and upwardly return bent to provide a finger-receiving opening outlined at its upper edge by said tab return bend.

8. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said handle panel and transverse panel being formed of double thickness.

9. A bottle carrier comprising a transverse tubular portion including top, bottom and side walls, one of said side walls being taller than the other, a transverse panel carried by the upper end of said tall side wall, and an upwardly extending handle panel carried by the free end of said transverse panel, said top wall and transverse panel having registering bottle-receiving apertures therein, said tubular portion, transverse panel and handle panel being formed from a single blank including an end portion complementary to and return bent upon said handle panel and transverse panel, said return bent end portion being apertured in registration with the apertures of said transverse panel.

10. A bottle carrier formed from a single apertured blank bent transversely at spaced points, a locking tab struck from an intermediate portion of said blank in longitudinal alignment with an aperture and adapted to interlock with an end portion of said blank adjacent said aligned aperture to define a tubular portion apertured at its upper portion, the upper portion of said blank including a laterally bent panel having apertures registering with said tube aperture, and an upwardly projecting handle portion.

11. A bottle carrier formed from a single blank and comprising a transversely extending tubular portion at its lower end, an intermediate transverse portion spaced above said tubular portion and a handle portion at its upper end, said transverse portion and the upper part of said tubular portion having registering bottle-receiving apertures therein.

12. A bottle carrier formed from a single blank and comprising a transversely extending tubular portion at its lower end, an intermediate transverse portion spaced above said tubular portion and a handle portion at its upper end, said transverse portion and the upper part of said tubular portion having registering bottle-receiving apertures therein, and a locking tab formed integrally with the intermediate portion of said blank and interlocked with an end portion of said blank adjacent one of said openings to retain the lower portion of said blank in tubular shape.
